PROPELLING MEANS

Robert Doussain, Villeurbanne, France

Application March 29, 1946, Serial No. 658,335
In France September 26, 1945

2 Claims. (Cl. 170—160.48)

1

My invention relates to variable pitch propellers and has for its object a system providing for the standardization of its very design by ensuring a standardization of the different elements of these propellers.

My invention covers also a series of arrangements allowing this standardization and this simplification to be reached.

According to my invention, the variable pitch propeller is mounted in a manner such that a propeller including a predetermined number of blades may be replaced by a propeller having any other number of blades. A further object of the invention is to provide standard socket units comprising a rotatable blade carrying member and a speed reducing mechanism for a proper pitch adjustment speed reduction, each socket unit being detachably anchored in the propeller hub structure for removal therefrom as a unit.

My invention will be better understood by referring to the following description and accompanying drawing showing by way of example a form of execution of my invention.

Said description will make further features and advantages of my invention appear clearly.

In said drawings:

Fig. 1 is an end view of a shaft carrying a four-blade propeller.

Fig. 2 is a view similar to Fig. 1, partly in section, of a propeller with six blades mounted on a shaft.

Fig. 3 is a partly elevational, partly sectional end view on an enlarged scale of the propeller shown in Fig. 2.

Fig. 4 is a cross-sectional side view of the blade carrier block shown in Fig. 3 and of the shaft on which said blade carrier is mounted with the interposition of a sleeve, the view being taken on the vertical center line of Fig. 3.

Fig. 5 is a cross-sectional side view constituting a continuation of Fig. 4 from the line Y—Y and particularly showing the transmission means controlling the variations in pitch.

Fig. 6 is an end view of one of the blade carrying blocks and shows a speed reducer of the Eade type incorporated in the blade carrying block.

Reverting to the drawings, the fluted shaft 1 is adapted to carry a propeller. To this shaft is rigidly secured a sleeve 2 with inner flutings forming part of the hub permanently fitted on the shaft. This sleeve may be easily machined and its weight may be very small. The sleeve 2 includes a vertical flange provided with a number of claws 55 preferably as large as possible,

2

At 41 are shown the securing nuts. The shaft 1 may be hollow in which case it receives at its end a ring 40 for securing the sleeve 2 to the shaft 1 with two centering cones 56, 57. The sleeve 2 is adapted to receive the removable hub member proper 3.

According to my invention, there is provided a set of hub members each of which corresponds to a propeller comprising a certain number of blades. Whatever may be the number of blades, the execution of the central part of the hub member is the same, so that it may be secured without any modification of the sleeve 2 on to the latter. In Figs. 1 and 2 there are shown respectively a four-blade hub and a six-blade hub secured to the same sleeve 2. It is apparent that this arrangement allows changing the propeller simply by unscrewing the nuts 41 and by fitting the desired hub member over the sleeve 2.

20 The hub member proper 3 includes according to the number of its blades a corresponding number of seats 58 adapted to receive blade carrying socket units. Each socket unit is constituted by a plurality of assembled parts. One of these parts 3a is formed by a sleeve screwed into the seat formed by the removable hub member 3 through its lower edge, while the upper edge of part 3a is provided with a bead 59 inside which are mounted the bearings. One of these bearings 60 including rollers is adapted to damp the action of centrifugal forces while the other bearing 61 including balls is adapted, in association with a third bearing including rollers 62 located towards the bottom of the seat, to provide the blade with the required freedom of rotation. The part of the socket unit receiving the blade is constituted by a rotatable member 4 provided with two cylindrical concentric parts connected by an annular wall perpendicular to the axis of the two cylinders. The inner cylindrical part 4b of member 4 extends downwardly under the form of a sleeve 63 and the above-mentioned bearing 62 is inserted between the latter and the lower end of the sleeve 3a. The outer cylindrical portion of socket member 4, surrounding sleeve 3a is provided inside its lower outer edge with a screw thread inside which may be screwed a removable extension 4a provided with a bead 51 carrying the second race of the bearing 60. The upper part of 35 the outer cylindrical portion of socket member 4 is also provided with an inner thread engaging the lower flange of the blade 5 which engages the gap between said threaded upper part of the outer cylindrical portion of socket member 4 and an annular projection 4b providing for the cen-

tering of the blade in association with the upper edge 4c of the upper part of the outer cylindrical portion of socket member 4. With this manner of mounting the elements, it is apparent that the anchoring of the blade is separate from the bearing adapted to damp the effect of centrifugal force and from those which ensure the degree of rotary freedom required for the change in pitch.

The change in pitch is provided by the engagement of the pinion 10 meshing automatically with the conical tooth-work 12 of a bevel wheel 11, when the blade carrying socket unit is being mounted. The pinion 10 is fitted over the end of a shaft 6 mounted in the cylindrical inner space of the rotatable socket member 4 through the agency of roller bearings 64. This pinion may control directly the rotation of the rotatable socket member 4 and consequently that of the blade 5. However, as explained at the beginning of the specification, there are provided according to my invention speed reducing means associated with each blade-carrying socket unit. Said reducing means may be of the Eade type as illustrated by way of example in the drawings. 8 designates a gear eccentrically carried by the shaft 6; 7 designates the inner tooth-work of the sleeve 63 and 9 and 9a the centering device for the gear 8. In Fig. 6 is shown in plan view the manner of executing said speed reducing means. It includes a guiding cross piece 52 adapted to slide from the left hand side to the right hand side of Fig. 6. The gear 8 includes two guiding members 68 adapted to engage slide-ways 54 cut inside the body of the cross piece 52. Thus the gear 8 is capable of receiving only a circular translational movement.

The drive of the bevel wheel 11 is produced by means of a stationary control device such for instance as a jack of the hydraulic, electric or mechanical type.

It is to be understood that the above described embodiment of my invention is for the purpose of illustration only, and various changes may be made therein without departing from the spirit or scope of the invention.

What I claim is:

1. A variable pitch propeller comprising in combination with a propeller shaft and a selected number of propeller blades, a bevel wheel disposed around said propeller shaft, control means for the pitch adjustment acting on said bevel wheel, a hub structure having a removable hub portion forming a number of seatings corresponding to the number of blades, a number of standard socket units corresponding to the number of blades, each socket unit having a sleeve member detachably fastened in said seating and a blade carrying member rotatably mounted within said sleeve member and carrying one of said blades, a bevel gear mounted within each rotatable member in order to be driven by said

bevel wheel, and a speed reducing gearing interposed between each bevel gear and each rotatable member.

2. A variable pitch propeller comprising in combination with a propeller shaft and a selected number of propeller blades, a bevel wheel disposed around said propeller shaft, control means for the pitch adjustment acting on said bevel wheel, a hub structure having a removable hub member forming a number of seatings corresponding to the selected number of blades, a number of standard socket units corresponding to the selected number of blades, each socket unit having a sleeve member detachably fastened in one of said seatings and a blade carrying member rotatably mounted within said sleeve member and carrying one of said blades, said rotatable member having a cylindrical central portion extending within said sleeve member and an annular outer portion surrounding said sleeve member, at least one bearing between said annular portion and said sleeve member adapted to take the thrust due to centrifugal force, at least one bearing between said central portion and said sleeve member adapted to take the lateral thrust of the blade, a bevel gear mounted on a shaft disposed within said central portion of the rotatable member of each socket unit, and a speed reducing mechanism interposed between said bevel gear and said central portion of the rotatable socket member.

ROBERT DOUSSAIN.
